PUMP

John E. Stevens, New York, N. Y.

Application November 23, 1942, Serial No. 466,625

11 Claims. (Cl. 103—72)

This invention relates to pumps, and aims to provide a novel pump structure whereby a practical and efficient pump may be made which is extremely simple in construction and operation. The general principle of the invention is the utilization of a notched or cogged belt trained about a pair of rollers, drums, pulleys, or the like of unequal size, so that when the teeth of the belt pass around the smaller roller the water caught between successive rows of teeth is squeezed out. The belt may be made of any suitable flexible material or combination of materials, of which rubber may be cited as one example.

The above and other objects will become apparent in the description below, wherein characters of reference refer to like-numbered parts in the accompanying drawing which forms a part hereof. It is particularly to be noted that the drawing is intended to serve the purpose of illustration only and that it is neither intended nor desired to limit the invention necessarily to the specific details of construction shown in the drawing, excepting insofar as such details may be incorporated in the appended claims.

Referring briefly to the drawing,

Figure 1 is a longitudinal cross-sectional elevational view of the pump.

Figure 2 is a cross-sectional view taken on the line 2—2 of Figure 1.

Figure 3 is a cross-sectional view taken on the line 3—3 of Figure 1.

Figure 4 is a cross-sectional view taken on the line 4—4 of Figure 1.

Referring in detail to the drawing, the numeral 10 shows the pump housing, which comprises essentially a shell 11 enclosing one side, the top and bottom of the pump, and a panel or cover 12 secured against the periphery of the shell 11, by any suitable means such as, for instance, the screw bolts 13. A supporting base or pedestal 17 is integral with the shell 11.

A shaft 14 is supported in bearings supported in the shell 11 and panel 12, respectively, and has keyed thereon a pulley or wheel 15. One end of the shaft 14 extends through an opening in the panel 12 to the outside thereof so that it may be driven by any suitable means such as, for instance, a motor or a crank handle, not shown. An inlet opening 16 is provided through the side wall of the shell 11 and is positioned below the shaft 14, as shown.

As is seen in Figure 1, that end of the pump housing in which the shaft 14 and roller 15 are mounted, is of greater height than the other end.

Against the inside of the side wall of the shell 11, at the reduced end of the housing 10, a member 18 is mounted. In outer conformation this member is of the same curvature as the curved shell at that end so that it registers snugly within the shell. The member comprises a base or plate portion 19 which lies flush against the shell side wall. Extending from this plate 19 is an outer wall 20. Also extending from the plate 19 is a block portion 21, whose converging side walls 22 are parallel with the inner side walls 23 of the wall 20. The reduced end of the block 21 is gouged out to provide a cylindrical surface 24. A cover plate 25 is adapted to be screwed against the member 18. This plate 25 and the base plate 19 have opposed openings 26 in which pins or spindles 27 of a roller 28 register rotatably, the surface of the roller registering rotatably within the cylindrical gouge 24 of the block 21. With the roller 28 thus positioned, it is apparent that a channel 29 of constant depth and width is formed within the member 18 and covered by the plate 25, the inlet to this channel being taken at the point 30 and the outlet at 31.

25 A belt 32 is trained about the wheel 15 and the roller 28. On its inner side, the belt 32 is provided with spaced teeth or cogs 33, and the belt is made of flexible material of any suitable kind such as, for instance, rubber. An outlet opening 34 is provided through the plate 19 and shell 11 adjacent the lower periphery of the roller 28, and a nipple 35 extends therefrom.

The operation of the pump is as follows. With the type of pump illustrated, a hose may be attached to the inlet nipple 36 of the inlet 16 and the open end of the hose, not shown, placed into the water to be pumped. The shaft 14 is then rotated by any suitable means, not shown, in a clockwise direction (Figure 1). As the belt then travels in its path, it is to be noted that the teeth 33 thereof are brought together as soon as they begin to pass about the reduced roller 28, and the air which is thus squeezed out of that space is forced out through the outlet 34; thus a suction is created within the pump housing. When a sufficient suction has thus been formed, water will begin to be sucked through the inlet 16 and continued operation will force the water out through the outlet 34 on the same principle just mentioned in regard to the air. It is apparent that the belt 32 is readily operable at variable speeds, and the rate of pumping may therefore be controlled by the speed of rotation of the shaft 14. Since there are no metal contacts, it is obvious that the belt may be operated

at high speed. The volumetric efficiency of all rotary pumps is dependent upon the seal between the pressure side of the pump and the suction side. In the instant pump, as the belt race 29 in the discharge casing may be made of any length desired, and as the belt completely fills the raceway, the leakage can be maintained at a minimum.

This pump has a wide field of applications and it can be built for hand or motor power. By mounting it in such position that the larger end is set into the water with the reduced end positioned thereabove out of the water, it is obvious that it would function efficiently as a deep well pump by simply elongating the housing and using a long belt. Obviously, modifications in form and structure may be made without departing from the spirit and scope of the invention.

As a means to tend to guide the water within the housing toward the belt and into the spaces between the teeth 33, a deflector 37 is provided. This comprises simply an angle-shaped sheet of any suitable material secured to the outer wall of the block 21 just above the inlet 30 to the channel or raceway 29. This is especially useful when the belt is traveling at high speed and is consequently agitating the water within the housing.

It is further to be noted that the device could function with both roller and pulley of the same diameter, although in that case it would not be as efficient nor, probably, as practical as in the case illustrated.

I claim:

1. A pump comprising a housing having a rotatable shaft provided with a pulley rigid thereon and mounted in one end of said housing, a roller mounted in the other end of said housing, a belt of flexible material trained about said roller and pulley and having longitudinally spaced teeth on the inner surface thereof, a casing secured to said housing and surrounding said roller, said casing having a belt raceway formed therein of the same depth and width as said belt, said housing having an inlet opening adjacent said pulley and an outlet opening adjacent said roller.

2. A pump comprising a housing having a rotatable shaft provided with a pulley rigid thereon in one end thereof and a roller mounted in the other end of the housing, the diameter of said roller being less than that of said pulley, a belt of flexible material trained about said roller and pulley and having longitudinally spaced teeth on the inner surface thereof, a member secured to said housing around said roller and having a belt raceway extending therethrough, said raceway being of the same depth and width as said belt, said member and said belt registering in said raceway sealing the pulley side of said housing from the roller side thereof, said housing having an inlet opening therethrough adjacent said pulley and an outlet opening therethrough adjacent said roller.

3. A pump comprising a housing having a rotatable pulley in one end and a roller in the other, a belt of flexible material trained about said roller and pulley and having spaced projections on the inner side thereof, said housing having an inlet adjacent said pulley and an outlet adjacent said roller, and sealing means between said roller and pulley.

4. A pump comprising a housing having a pulley at one end and a roller at the other end,

a belt of flexible material trained about said roller and pulley and having longitudinally spaced teeth on the inner surface thereof, a wall dividing said housing into two compartments, one of said compartments containing said pulley and the other said roller, said housing having an inlet opening into said pulley compartment and an outlet opening into said roller compartment, said wall having a pair of opposed openings therethrough, said belt passing through said openings, said wall openings being of the same depth and width as said belt, said pulley being adapted to be rotated to actuate said pump.

5. A pump in accordance with claim 4, wherein one of said wall openings is provided on the pulley side with a deflector consisting of an angle-shaped member having one arm thereof extending angularly outward therefrom.

6. A pump in accordance with claim 4, wherein said teeth are tapered toward the free extremities thereof.

7. A pump comprising a housing having a pair of spaced apart rotatable pulleys, a partition dividing said housing into two compartments, one of said pulleys being positioned in each compartment, said partition having a pair of spaced openings therethrough, a belt of flexible material trained about said pulleys and having spaced teeth on the inner side thereof, said belt passing through said openings and being of the same cross-sectional dimensions as said openings to seal said openings, said housing having an inlet opening into one of said compartments and an outlet opening into the other.

8. A pump comprising a housing having a rotatable pulley in one end and a roller in the other, said roller having a smaller diameter than said pulley, a belt of flexible material trained about said roller and pulley and having outwardly tapering spaced teeth on the inner side thereof, said housing having an inlet adjacent said pulley and an outlet adjacent said roller, and sealing means between said roller and pulley.

9. A pump comprising a housing having a rotatable pulley in one end and a roller in the other, said roller having a smaller diameter than said pulley, a belt of flexible material trained about said roller and pulley and having cog-like projections thereon extending laterally across said belt on the inner side of said belt, said housing having an inlet adjacent said pulley and an outlet adjacent said roller, and sealing means between said roller and pulley.

10. A pump comprising a housing having a rotatable pulley in one end and a roller in the other, said roller having a smaller diameter than said pulley, a belt of flexible material trained about said roller and pulley and having laterally extending longitudinally spaced projections on the inner side thereof, said housing having an inlet adjacent said pulley and an outlet adjacent said roller, and sealing means between said roller and pulley.

11. A pump comprising a housing having a rotatable pulley in one end and a roller in the other, a belt of flexible material trained about said roller and pulley and having spaced recesses on the inner side thereof, said housing having an inlet adjacent said pulley and an outlet adjacent said roller, and sealing means between said roller and pulley.

JOHN E. STEVENS.
